(57) **CLAIM**

The ornamental design for a clean out cover unit, as shown and described.

DESCRIPTION

FIG. 1 is a perspective view from above of our new design for a clean out cover unit.

FIG. 2 is another perspective view of our new design for a clean out cover unit.

FIG. 3 is top plan view of the cover unit of FIG. 2.

FIG. 4 is a front view of the cover unit shown in FIG. 3.

FIG. 5 is a rear view of the cover unit shown in FIG. 3.

FIG. 6 is a bottom plan view of the cover unit shown in FIG. 2.

FIG. 7 is a side view of the cover unit shown in FIG. 6; and, FIG. 8 is an opposite side view of the cover unit shown in FIG. 6.

The broken line elements shown in FIG. 1 are environmental, and form no part of the invention.
